WATER COOLED SLIDE RAIL FOR REHEATING FURNACES

Filed June 21, 1928

UNITED STATES PATENT OFFICE

FRIEDRICH CARL SIEMENS, OF BERLIN, GERMANY

WATER-COOLED SLIDE RAIL FOR REHEATING FURNACES

Application filed June 21, 1928, Serial No. 287,283, and in Germany June 27, 1927.

This invention relates to a further development of the water-cooled slide rail for reheating furnaces covered by the United States Patent No. 1,572,566. According to 5 the said patent the water-cooled supports of the slide rails, extend in the longitudinal direction of the slide rails and parallel thereto, that is, perpendicularly.

Now the present invention consists primarily in arranging these cooled supports in a position differing from that given in the afore-mentioned patent, at any convenient angle to the slide rails. This invention may be carried out in various ways. Thus for example the individual supports arranged one behind the other in the longitudinal direction of the slide rail, may be placed obliquely in such a manner that they are inclined to the rails on one side and the other alternately, for the purpose of protecting the rails against lateral thrusts. They may however alternatively be formed by tubes extending perpendicularly to the longitudinal axis of the furnace, these tubes then being bent in various ways to form the supports, the tubes being looped, U-shaped, V-shaped or the like. This gives a better supporting of the slide rails against laterally acting thrusts, moreover a more convenient arrangement of the bends of pipes connecting the individual cooling tubes of the supports, which in this arrangement must be arranged at the sides of the furnace and not underneath the furnace, as in the United States Patent No. 1,572,566.

The accompanying drawings illustrate various constructional forms of the invention.

In all the figures, the furnace chamber *a* is shown in cross section, and the water-cooled slide rails extending in the longitudinal direction of the furnace chamber are indicated at *b*.

Now in the constructional form according to Fig. 1, the water-cooled supports *c* are placed obliquely in relation to the slide rails *b*, in such a manner that one support is inclined on the left and the other on the right alternately in relation to the said slide rails,

whereby a more reliable supporting of the rails against lateral thrusts is obtained.

In the constructional form shown in Fig. 2, the slide rails *b* are supported upon tubes *c* passing across the furnace perpendicularly to them, these tubes being bent in the centre into loops *d*, which here form the actual supports. Since in this case the brickwork of the furnace also assists in carrying the slide rails at the sides, the supporting of the slide rails by the tubes *c* may be of lighter construction.

In the constructional form according to Fig. 3, the tubes *c* carrying the slide rails *b* are bent out in the middle at *e* into the form of a U in such a manner that the two limits of the U serve as carrying-supports for the tubes *c*, which at the other end are supported in the brickwork of the furnace.

The constructional form shown in Fig. 4, is intended for furnaces in which rather heavy ingots are to be heated. The tube *c* which is here likewise utilized for carrying the slide rails *b*, is here bent into an inverted U for each slide rail, the further supporting by the brickwork of the furnace, as adopted in the case of Figs. 2 and 3, being here abandoned.

Fig. 5 differs from Fig. 4 merely in the fact that the inverted U-shaped supports *f* of the slide rails *b* are pulled out into an inverted V-shape.

The constructional form according to Fig. 6 is intended for a furnace for particularly long and heavy ingots, for which three slide rails *b* are here provided. These slide rails may of course be carried in the same way as in Fig. 4 for example, but in the constructional form shown in Fig. 6 the U-shaped supports are the other way up, so that the tube *c* may be supported at both ends by the masonry of the furnace. The U-shaped supports *f* are here so close together that the slide rails *b* can be supported in the upper end of the slot between the two limbs of the U.

It is of course obviously possible also to design other constructional forms of the present invention, as the figures included in the accompanying drawings are merely given by way of example.

What I claim is:—

1. A water-cooled slide-way for reheating furnaces, comprising the combination with horizontal tubing extending in the longitudinal direction of the furnace and constituting slide rails of tubular supporting members for the slide rails, said tubular supporting members extending transversely to and also downwardly from the slide rails.
2. A water-cooled slide-way for reheating furnaces, as set forth in claim 1, in which the tubular supporting members are inclined with their lower ends on opposite sides of the slide rails.
3. A water-cooled slideway for reheating furnaces, as set forth in claim 1, in which the tubular supporting members are alternately inclined to opposite sides of the slide rails.
4. A water-cooled slide-way for reheating furnaces, comprising the combination with horizontal tubing constituting slide rails extending in the longitudinal direction of the furnace, of tubular supports for the slide rails, arranged in planes transverse to the longitudinal axis of the furnace and comprising horizontal bearing elements on which the slide rails rest and downwardly directed tubular limbs constituting supports for the horizontal bearing elements.
5. A water-cooled slide-way for reheating furnaces, comprising the combination with horizontal tubing extending in the longitudinal direction of the furnace and constituting slide rails, of looped tubular supports for the slide rails, arranged in planes transverse to the longitudinal axis of the furnace and comprising horizontal bearing elements on which the slide rails rest and downwardly directed tubular limbs constituting supports for the horizontal bearing elements.
6. A water-cooled slide-way for reheating furnaces, comprising the combination with horizontal tubing extending in the longitudinal direction of the furnace and constituting slide rails, and U-shaped tubular supports for the slide rails, arranged in planes transverse to the longitudinal axis of the furnace and comprising horizontal bearing elements on which the slide rails rest and downwardly directed tubular limbs constituting supports for the horizontal bearing elements.
7. A water-cooled slide-way for reheating furnaces, comprising in combination horizontal tubing constituting slide rails and V-shaped tubular supports for the slide rails, arranged in planes transverse to the longitudinal axis of the furnace and comprising horizontal bearing elements on which the slide rails rest and downwardly directed tubular limbs constituting supports for the horizontal bearing elements.

In testimony whereof I have signed my name to this specification:

FRIEDRICH CARL SIEMENS.
